UNITED STATES PATENT OFFICE.

SYLVESTER W. SHELDON, OF NEW YORK, N. Y.

BARREL-COVER.

SPECIFICATION forming part of Letters Patent No. 241,075, dated May 3, 1881.

Application filed December 10, 1880. (No model.)

To all whom it may concern:

Be it known that I, SYLVESTER W. SHELDON, of the city, county, and State of New York, have invented a new and useful Improvement in Barrel-Covers, of which the following is a specification.

Figure 1 is a plan view of the improvement. Fig. 2 is a sectional elevation. Fig. 3 is an under-side view.

Similar letters of reference indicate corresponding parts.

The object of this invention is to furnish barrel-covers so constructed as to be conveniently handled and kept in place upon a barrel while having their upper and lower sides level, so that they can be packed in small space for storage and transportation.

In the accompanying drawings, the cover A is formed of a board an inch (more or less) in thickness.

In the middle part of the upper side of the cover A is formed a ring-groove, B, of a depth equal to about two-thirds of the thickness of the board A. The top of the part C, surrounded by the groove B, is cut off to such a depth that the upper surface of the plate D, attached to the said middle part, will be flush with the upper surface of the cover A. The

plate D is made a little larger than the inner circumference of the groove B, so that its edge 30 will project over the said groove, so as to be readily grasped with the fingers. The edge of the plate D is rounded off to prevent it from cutting the fingers that grasp it. The plate D has a circular recess formed upon its lower 35 side, to receive the center part, C, and give the said plate a firmer seat. The plate D is secured in place by a rivet passing through its center and the center of the cover A, as shown in Fig. 2, or in any other convenient manner. 40 In the lower surface of the cover A, near its edge, is formed a groove, E, of a depth equal to about one-half the thickness of the cover A, to receive the chimes of the barrel, and thus keep the cover in place.

Having thus described my invention, I claim as new and desire to secure by Letters Patent—

The ring-grooved transferable barrel-cover A E, having on the upper side the ring-groove B and central part, C, the latter provided with 50 a projecting top plate, D, as shown and described.

SYLVESTER W. SHELDON.
